UNITED STATES PATENT OFFICE.

ARTHUR STOCKSTROM AND ISAAC VERNON BRUMBAUGH, OF ST. LOUIS, MISSOURI,
ASSIGNORS TO AMERICAN STOVE COMPANY, OF ST. LOUIS, MISSOURI, A CORPOR-
ATION OF NEW JERSEY.

GAS BURNER.

Application filed August 30, 1926. Serial No. 132,534.

This invention relates to certain improvements in gas burners whereby the following objects and purposes are attained.

The primary purpose of the present invention is to combine an outer cast iron member with an inner member consisting of an alloy enabling the inner member to be die cast for the purpose hereinafter set forth.

The purpose of the present invention is to make the outer member of cast iron and the inner member of aluminum alloy, thus enabling the inner member to be die cast.

We were therefore confronted with the manufacturing problem of the production of a burner constructed in the manner hereinafter described.

In order to make the inner member of the form herein disclosed we have found it to be necessary to die cast it instead of the usual mold casting, and therefore it must be composed of a metal that is readily capable of being die cast. We also found that a metal that is capable of being die cast has a melting point below that of the gas flame, whereas the outer member of the burner is constructed of cast iron which has a melting point above that caused by the burning gas.

Therefore the problem to be solved was to so construct this aluminum alloy and to so connect it with the cast iron outer member that when in operation it would be kept at a temperature below its melting point, for otherwise it would be quickly destroyed.

We also found that when the inner member is die cast, it does away with machines and the labor for cutting the parts thereof, thus greatly decreasing its cost of production over the ordinary method of mold casting, and it further produces a non-corrodible member with its inherent advantages.

Other objects of the invention will be understood from the following description.

In the accompanying drawings:

Figure 1 is a top plan view of our improved burner.

Figure 2 is a central vertical section of the burner, a cooking utensil being shown in dotted lines thereabove.

Figure 3 is an enlarged side elevation of the part carrying the ports, the same being detached.

Figure 4 is an inverted enlarged plan view showing a part of the interior non-corrosive metal that is provided with the gas ports.

Figure 5 is a vertical central section of the improved burner showing a slight modification in its construction.

Figure 6 is a top plan view of Figure 5.

Our improved burner comprises essentially two parts, the interior member 1 and the exterior member 2, the latter having projecting therefrom the manifold 3. This manifold may extend in any desired direction without affecting the present improvement, though for convenience it is shown in the drawing as extended horizontally.

The member or part 2 is comprised of cast iron, while the interior part 1 is made of a non-corrodible material. This interior part 1 is annular in shape, thereby providing a vertical passage 4 through which passes the secondary air for supporting combustion. The primary air passes through the manifold 3 and the part 2 and is mixed with the gas as is well understood by those skilled in the art.

Attention is particularly called to the fact that the non-corrodible interior member 1 is provided with exterior teeth 5 that are radially disposed in respect to the axis of the said member. These teeth 5 form, of course, spaces 6 between them, and the teeth extend outwardly and upwardly at an angle and engage tightly a correspondingly inclined annular portion 7 formed on the exterior cast iron member 2. In this manner a plurality of ports are formed by the spaces 6, and these ports extend outwardly at an angle to the burner.

The inner wall of the interior member 1 is provided with a plurality of projections 8, through which projections ports 9 are formed, the said ports extending upwardly and inwardly at an angle to the ports. The interior member 1 is made separate from the interior member 2, and is provided with a downwardly extended portion 4, the lower end of the extended portion provided with exterior threads 10 that engage exterior threads 11 formed in the bottom 12 of the exterior member 2. It will be seen that in this manner the interior member is made annular in form and that the passage 4 has its lower end open for the passage of secondary air to the gas ports 9.

It is well known to those skilled in this art that where a burner has its ports made in cast iron, that the ports become corroded and to a certain extent partially closed, and that the

partially closing of these ports reduces the speed of the gas through the burner and thereby reduces the amount of air drawn into the manifold 3 by its passage therethrough. To the extent that the ports are partially obstructed by corrosion, the amount of air fed with the gas is correspondingly reduced and that the gas is therefore not provided with the proper quantity of air for its complete combustion, with the result that there is formed carbon monoxide. It is well understood also that carbon monoxide gas is very objectionable and if in sufficient quantities, is extremely dangerous.

This interior portion 1 is composed of an aluminum alloy that has a melting point of 1075° F. It is well known that the temperature of a gas flame is over 2000° F. It is therefore necessary to provide means for keeping the temperature of this interior non-corrodible alloy below its melting point. For this reason the burner is made relatively deep, which provides sufficient length for the passage of the secondary air therethrough to cause it to keep the temperature of the alloy considerably below its melting point. The air passing through it of course cools it, and the member is further cooled by reason of the intimate contact of its screw threaded lower end with the exterior member 2 through which the incoming mixed gas and air flow. The gas being relatively cool, strikes the member 1 in addition to the effect of the secondary air, and we find that this alloy member is kept at a temperature considerably below its melting point.

Further this alloy member is screwed down to bring the teeth 5 in intimate contact with the cast iron member 2 and also form a gas tight relation with the inclined member 7 of the part 2.

For the purpose of reducing the cost of the burner and avoiding the necessity of machine work in it, the non-corrodible alloy interior member 1 is die cast so that machine work on it is unnecessary and the same fits snugly the inclined part 7 when it is in position. To form this interior part 1 with machinery would be quite a complicated job, calling for the expert labor and also calling for machines adapted to perform the work. By die casting it, all the machine and expert labor is done away with, making the construction much cheaper than it would be otherwise.

The object of the interior ports 9 is to cause the flame to strike the center of the utensil 14, and spread outwardly while the exterior ports or passageways flow outwardly and cover the outer portion of the utensil. Attention is directed to the fact that the outlet ends of the passages 5 and 9 respectively are located quite a distance apart for the purpose of causing the flames from the two passages from merging immediately at the bottom of the utensil 14, and for the purpose of caus-

ing the fuel from the passages 9 to flow first to the center of the utensil. It will also be noted that the member 4 is composed of relatively thin metal and in order to elongate the passages 9 so that the fuel flowing therefrom will be directed inwardly at a sufficient angle to reach the bottom of the utensil 14, the inner wall of the member 4 is provided with the projections 8, thereby elongating the passages 9 and accomplishing the above function. The flame from the interior ports 9 necessarily striking the center of the utensil, flows outward and mingles with the outwardly flowing flame from the passages and the ports 6, thereby completely covering the whole bottom surface of the utensil. This construction absolutely avoids having a cooling center in the utensil as is the case with the ordinary gas burner.

In Figure 2 our burner is shown full size from which it will be noted that it is much smaller than the ordinary gas burner which makes it highly efficient for cooking operations because of its relatively smaller diameter that causes the flame to engage the complete bottom of the utensil, striking the utensil in the center and then spread over the whole of its surface. By reason of this fact the flame has a longer period of contact with the utensil than is ordinarily effected by the prior constructions of gas burners.

By reason of the combination of the outwardly inclined passages 6 and the inwardly inclined passages 9 the fuel and flames from the said passages play upon the bottom of the utensil 14 very differently from what it would be were the outlet passages 9 combined with vertically arranged passages. Where the burner is provided with vertically arranged passages adjacent the outlets of the passages 9, the fuel and flames spread in both directions, that is they spread inward toward the center of the utensil and spread outward, and the flame from the vertical passages would commingle with the flame from the passages 9. This condition is different from the construction here shown to an exaggerated extent when a plurality of vertical passages is provided, thereby providing a superabundance of fuel and flames which spread over the whole bottom of the utensil, irrespective of the action of the inwardly extending passages 9. It in effect destroys the action of the inwardly extending passages 9, making them wholly unnecessary. Therefore the specific construction here shown being the combination of inwardly extending passages in the inner member and outwardly extending passages in the outer member, the outlets of the two passages being removed, makes a burner that operates very differently and is very different from a combination of inwardly extending passages and vertical passageways located adjacent each other in the manner shown in the patent to Kahn and Longfellow,

No. 769,389, September 6, 1904. It also enables a much smaller burner to be used just as efficiently as the much larger burner shown in the said patent. The burner here shown is 5 of a diameter that does not exceed the diameter of the first vertical row of openings, while the patent shows four additional vertical openings. This is due to the fact that the inner openings extend inwardly at an angle and 10 cause the fuel and flame to spread only inwardly, whereas the flame from the vertical openings spreads in both directions.

We therefore believe our burner to be a new 15 type of gas burner which has a novel function, as we have herein set forth.

In Figures 5 and 6 a slight modification in the construction is shown. This modification consists in providing the interior member 1 with its inner wall formed in an outward 20 curve as shown, and member 2 having its upper portion inclined outwardly as shown at 2', the members otherwise being substantially the same construction as herein explained. It 25 will also be noted that in the modification the upper ends of the passages are shown slightly open and the gas will flow more directly upward than will be the case with the construction shown in Figures 1 to 4 inclusive.

The inner member 1 is composed of an aluminum alloy. This alloy is readily adapted to make a good clean die casting.

We desire it understood that modifications and changes ~~may~~ be made in the construction herein shown and described without departing from the spirit and scope of our invention, so long as said changes in construction are 35

within a fair interpretation of the appended claim.

Having thus described our invention, what is desired to claim and secure by Letters Patent is:

A gas burner of the type herein described, comprising a cast-iron outer vertically arranged annular member having the upper end of its inner wall extending outwardly, an inner vertical annular member composed of alloy provided with a downwardly extending wall of smaller diameter than said outer member, the upper end of said wall extending outwardly and the under side of said extension provided with depending teeth in engagement with the said outwardly extending portion of the said outer cast-iron member, thereby forming outwardly extending gas-passages and the outwardly extending portion of the inner member also provided with outwardly extending gas-openings, said inner alloy member having a melting point normally below that of the burning gas, the lower end of the inner member in tight contact with the said outer member, whereby the inner member is cooled by heat conduction of the cast-iron member and maintained at a temperature below its melting point by said contact, by air flowing through the inner member, and by mixed air and gas striking the outer side of the inner member, substantially as described.

In testimony whereof we hereunto affix our signatures.

ARTHUR STOCKSTROM.
ISAAC VERNON BRUMBAUGH.
